(57) **CLAIM**

The ornamental design for a diamond-studded kickbar, as shown and described.

DESCRIPTION

FIG. 1 is a front elevational view of a pair of diamond-studded kickbar in use on a shoelace, showing my new design;

FIG. 2 is a front perspective view thereof;

FIG. 3 is a rear perspective view thereof;

FIG. 4 is a front elevational view thereof;

FIG. 5 is a rear elevational view thereof;

FIG. 6 is a side elevational view thereof;

FIG. 7 is an opposite side view of that show in FIG. 6;

FIG. 8 is a top plan view thereof;

FIG. 9 is a bottom plan view thereof;

FIG. 10 is a front perspective view of a second embodiment of the diamond-studded kickbar of FIGS. 1-9;

FIG. 11 is a rear perspective view of FIG. 10;

FIG. 12 shows a front elevational view of a diamond-studded kickbar when used to decorate a bracelet or wristband; and,

FIG. 13 shows a front elevational view of a diamond-studded kickbar when used to decorate a necklace or neckband.

The broken line showing in FIGS. 1, 12 and 13 are for illustrative purposes only and form no part of the claimed design.
